GAME APPARATUS

John G. Frost, Seattle, Wash.

Application June 26, 1952, Serial No. 20,365

Term of patent 14 years

(CL. D34—5)

To all whom it may concern:

Be it known that I, John G. Frost, a citizen of the United States of America, residing at Seattle, in the county of King and State of Washington, have invented a new, original, and ornamental Design for a Game Apparatus, of which the following is a specification, reference being had to the accompanying drawings, forming part thereof.

Fig. 1 is a top plan of a game apparatus, showing my new design;

Fig. 2 is a front elevational view thereof; and
Fig. 3 is a side elevational view thereof.

The drawing figures are lined to indicate transparency. The ends of the cylinders shown at the bottom in Figs. 2 and 3 are substantially the same in appearance as the ends of the cylinders shown at the top in Fig. 1.

I claim:

The ornamental design for a game apparatus, as shown.

JOHN G. FROST.
